UNITED STATES PATENT OFFICE.

ALFRED WAGNER, OF PHILADELPHIA, PENNSYLVANIA, ASSIGNOR TO GOTHAM SILK HOSIERY COMPANY, INC., OF NEW YORK, N. Y., A CORPORATION OF NEW YORK.

COURSE-CONTROLLING ATTACHMENT FOR KNITTING MACHINES.

Application filed December 22, 1923. Serial No. 682,137.

This invention relates to improvements in a course controlling attachment for knitting machines designed to operate automatically to control the number of courses to be 5 knitted and to permit variation in the stitching of successive courses.

The object of the invention is to provide a course controlling attachment for knitting machines which is simple in construction, 10 capable of being readily and easily applied to knitting machines of common construction, and which is efficient in operation, for controlling the number of courses to be knitted in a knitted article of apparel for 15 any desired character of stitching.

A further object of the invention is to provide an attachment of the character referred to for automatically arresting the operation of a knitting machine when a desired length of a knitted article has been 20 completed.

Further objects of the invention will appear more fully hereinafter.

The invention consists substantially in the 25 construction, combination, location and relative arrangement of parts all as will be more fully hereinafter set forth, as shown in the accompanying drawings and finally pointed out in the appended claims.

30 Referring to the accompanying drawings, Fig. 1 is a view in side elevation of a portion of a knitting machine showing the application thereto of an automatic course controlling attachment embodying the principles of my invention.

Fig. 2 is a view in top plan of the construction shown in Fig. 1.

Fig. 3 is a broken detail view in vertical transverse section on the line 2—2, Fig. 1, 40 looking in the direction of the arrows.

Fig. 4 is a broken detail view in side elevation parts in section on the line 4—4, Fig. 2, looking in the direction of the arrows and showing a portion of the course controlling 45 attachment in elevation.

Fig. 5 is a broken detail view in top plan showing the connections of the attachment and its associated parts for effecting the actuation of the machine arresting member.

50 Fig. 6 is a detached broken detail view showing the manner of automatically actuating the attachment.

Fig. 7 is a broken detail view in vertical section on the line 7—7, Fig. 5, looking in 55 the direction of the arrows.

The same part is designated by the same reference numeral wherever it occurs throughout the several views.

In the manufacture of knitted articles of 60 wearing apparel of various kinds, it is a common practice to knit a given length of the article with one kind or characteristic of 65 stitch and then for another or succeeding section or portion of the length of the knitted article to employ a stitch of a different characteristic, and so on until the entire length of the knitted article is completed. Heretofore, so far as I am aware, 70 the universal practice has been to continue the knitting of the article with a given kind or characteristic of stitch until the desired length of the course is attained, and for the operator of the knitting machine to determine solely by his eye and his experience 75 when the desired length or course is completed. The machine is then arrested and the character of the stitches is altered, in a well-known manner, so as to produce the next course of stitching in the length of the 80 article in a different character or kind of stitching, the operator again determining by his eye or experience when to arrest the knitting operation, i. e., when the desired length of course of the knitting with the varied style of stitching has been attained. 85

This universal custom and practice has resulted in the production of completed knitted articles which vary from each other in the lengths of corresponding courses of like 90 character of stitching. This defect results from dependence being placed on the human element involved in an operator determining by inspection when to effect an arrest of the machine in order to permit a change 95 being made in the character of the stitching to be employed. In other words, in the production of successive articles which are desired to have uniform lengths of courses of the same character of stitching, the uniformity in such lengths or courses is not 100 attained.

It is among the special purposes of my present invention to provide an attachment for knitting machines which controls automatically the point at which the machine is arrested to permit a change in the character of knitting to be made, thereby relieving the operator of the duty of effecting such arrest according to his own judgment, whereby in the use of the attachment, presently 105 110

- to be described, the arrest of the machine is made automatically at the same point in the length of the course of stitches for each succeeding article knitted on the machine, 5 with the result that knitted articles of uniform length are produced each having successive courses of uniform length but of relatively varying characters or styles of stitching.
- 10 In carrying out my invention, I propose to employ a traveling member driven from the main power shaft of the knitting machine through the usual or any ordinary or desired arrangement of gearing, and which corresponds in length of its action to a complete cycle of operation of the knitting machine required to produce a completed idea of knitted apparel. For example, if the knitted article to be produced is a stocking, then this movable member is of such length as to complete one cycle of operation during the knitting operations required to complete one stocking, and I provide means associated with the traveling member referred to which, at predetermined intervals in the complete cycle of operation thereof, and corresponding to successive courses to be produced in the knitted articles, effect the automatic arrest of the machine so as to permit the necessary alterations and changes in the well-known manner of the knitting devices to vary the character or style of the knitting employed in producing the next succeeding course in the knitted article.
- 35 In the accompanying drawings, I have shown one structure of course controlling attachment embodying my invention wherein the movable member referred to is shown in this instance as an endless chain device.
- 40 8. In practice, I employ for this purpose the usual narrowing chain forming part of the usual knitting apparatus, it being understood that this chain completes one cycle of its operation during the period the knitting machine is produced a completed knitted article. Where knitted articles of different lengths are produced on the same knitting machine, the narrowing chain 8 is replaced by other chains respectively, corresponding in length or cycle of operation to the length of the particular article to be produced.
- 45 In accordance with my invention, I propose to mount upon or secure to the chain 8 at suitable spaced apart intervals the blocks or stop buttons 9, which, in the case of the chain device 8 are in the form of an endless chain operating over sprockets, as indicated at 10, which is the usual arrangement in knitting machines. These blocks or stop buttons are brought at predetermined intervals of time in engagement with a rock arm 11 pivotally mounted as at 12 upon a fixed bracket or stand 13 suitably mounted upon a convenient part of the frame work of the knitting machine, such, for example, as
- the front rail 14. The free end of the rock arm 11 is arranged, when said rock arm is displaced by the engagement therewith of a stop button 9 (see Fig. 6), to engage the tail end 15 of a lever 16 which is pivotally mounted as at 17 upon a standard 18 forming part of the bracket 13. The upper end of the lever 16 is connected through an arm 19 and link 20 with the lower end of a lever 21 pivotally mounted at its upper end 75 upon a stud indicated at 22 carried by the short arm 23 of a bell crank lever 24, said bell crank lever being pivotally mounted at its angle on a stud 25 tapped into a bracket 26 or a portion 27 of the frame work of 80 the machine. The free end of the long arm of the bell crank lever 24 is connected as indicated at 28 with a longitudinally and vertically movable bar 29 which, at its upper end, is formed with a beveled or cam surface 30 (see Fig. 1), arranged to operate against a roller 31 having an axial pin 32, one end of which engages the member 33 which constitutes the stop bar for arresting the operation of a knitting machine. The roller or stud 31 is held and guided by means of a bracket 34 suitably fastened to a convenient part 35' of the frame work of the machine, the pin 32 carrying the abutment 31 working freely in a slot 35 formed in 85 said bracket.
- 90 Mounted upon a shaft 36 driven from the main power shaft of the machine is a member consisting of a disc portion 37 and a cam portion 38. The disc portion 37 is provided with a cylindrical rim surface, while the peripheral surface of the cam portion is provided with a cam projection 38' thereon (see Fig. 3). Carried by the arm 21 near its lower end are laterally projecting pins 100 39, 40. Pin 39 rides against the cylindrical peripheral surface of the member 37 while the arm 21 is normally maintained in position for the pin 40 to be retained out of peripheral contact with the cam member 38. When, however, the member 21 is rocked by the engagement of the arm 11 with lever 16, as above explained, the lever 21 is rocked or swung upon its fulcrum pin 22 in a direction to project the pin 40 into the 105 path of the cam surface 38 so that when said cam is rotated said lever 21 is rocked thereby, rocking the bell crank lever 24 upon its fulcrum 25 in a direction to project the bar 29 upwardly, thereby bringing the cam 110 surface 30 at the upper end of said bar into contact with the abutment 31, thereby causing the stop member 33 to be shifted endwise to effect, in the well-known manner, the arrest of the operation of the machine. The shift of the stop member 33 in the manner described is against the action of the usual spring contained in a casing 41 and connected by a link 42 with said member 33 to return or restore said stop member 115 120 125 130

to its initial position when the machine is again started and the parts restored to their normal positions.

The operation of the apparatus is exceedingly simple and is entirely automatic in effecting at the proper and predetermined intervals the arrest of the operation of the knitting machine. The machine is put in operation in the usual and ordinary manner and such operation continues with its knitting operations to produce the desired knitted article until a stop button 9 on the traveling member 8 actuates the arm 11, thereby through the connections above described effecting a shift of the stop member 33, whereupon the machine is arrested. The operator then arranges his knitting devices to accomplish any desired change in the character of the stitching. The machine is again put into operation and a second course of stitching of the changed variety is added to the length of the article being produced. When the desired length of such new course of stitching is attained, as predetermined by the spacing apart of the stop buttons 9 on traveling member 8, another stop button is brought into position to operate the arm 11 thereby again shifting the stop member 33 and arresting the machine to permit another shift or change in the knitting devices to produce a different character of stitch. This operation continues throughout an entire cycle of action of the machine corresponding to the length of operation of the traveling member 8. Consequently, each succeeding completed article turned out by the machine is not only of uniform length but the various successive courses of stitching of relatively different characteristics are all absolutely uniform in length of the courses and relation of the successive courses without depending upon the mere skill or attention of the operator to gauge the lengths or extent of said courses.

While I have shown and described in detail one structure of automatic course controlling attachment for knitting machines as an illustrative practical embodiment of my

invention, and one which I have found efficient in extensive use, I do not desire to be limited or restricted to the exact details of structure thereof as shown and described, but what I do claim as new and useful and of my own invention, and desire to secure by Letters Patent is:—

1. In a knitting machine, an arresting bar and a narrowing chain, in combination with means actuated by the narrowing chain to operate the arresting bar, said means including a shifting bar, an abutment carried by the arresting bar to be engaged by said shifting bar, a bell crank lever for actuating the shifting bar, and means actuated by the narrowing chain to operate the bell crank lever.

2. In a knitting machine, an arresting bar and a narrowing chain, in combination with means actuated by the narrowing chain to operate the arresting bar, said means including a shifting bar, an abutment carried by the arresting bar to be engaged by said shifting bar, a bell crank lever for actuating the shifting bar, a cam driven by the machine, and means actuated conjointly by the narrowing chain and the cam for operating the bell crank lever.

3. In a knitting machine, an arresting bar and a narrowing chain, in combination with means actuated by the narrowing chain to operate the arresting bar, said means including a stop on the narrowing chain, a rock arm arranged to be engaged by said stop, a lever engaged by said rock arm, a swinging rock lever operated by said first mentioned lever, a pin carried by the swinging rock lever, a cam to engage said pin, a bell crank actuated by said swinging rock lever, a bar actuated by the bell crank, and an abutment carried by the arresting bar arranged to be engaged by said bell crank actuated bar.

In testimony whereof I have hereunto set my hand on this 15th day of December A. D., 1923.

ALFRED WAGNER.
